PAPER-CUTTING KNIFE

Jay W. Joseph, Winston-Salem, N. C., assignor to
 Western Electric Company, Incorporated, New
 York, N. Y., a corporation of New York

Application November 10, 1948, Serial No. 59,233

5 Claims. (Cl. 30—292)

1

This invention relates to a device for cutting sheet material and more particularly to a hand tool for severing paper, cloth or similar sheet material.

The object of the invention is to provide a simplified manual cutter or trimmer which severs or slits sheet material by a mere forward, sliding motion of the cutting device.

In accordance with one embodiment of the present invention, a manually operable cutting device is provided having a handle with a lower jaw member and an upper spring-pressed jaw member hingedly mounted thereon. The upper jaw member has mounted therein a disc-shaped cutting blade secured between two knurled metal or rubber cylindrical friction rollers. The two rollers in contact with the relatively moving sheet of material drive the blade to perform the cutting or slitting operation as the sheet material to be cut or slit passes between the jaw members.

Other features and advantages of the invention will become apparent from the following detailed description taken in conjunction with the accompanying drawings in which:

Fig. 1 is a front elevation of a cutting device embodying the features of this invention;

Fig. 2 is a top plan view of the device shown in Fig. 1;

Fig. 3 is an end view of this device as viewed from the right end of Fig. 1;

Fig. 4 is a fragmentary sectional view taken along line 4—4 of Fig. 1; and

Fig. 5 is a perspective view of a slot-forming insert shown in Figs. 1 and 4 for receiving the lower portion of the cutting disc or blade.

Referring now to the drawings, the cutting device consists of a lower jaw 11 having an integral offset handle portion 12. A movable upper jaw 13 is bifurcated at the left end (Fig. 1) which fits over the lower jaw 11 and is pivotally secured thereto by a pin 14. The upper jaw 13 normally extends in parallel spaced relation with the right hand portion of the lower jaw 11. A steel leaf spring 15 is secured to an inclined portion of the lower jaw 11 by two machine screws 16 which pass through an intermediate spacer block 17. The steel leaf spring 15 serves to normally urge the jaw 13 toward the jaw 11. A vertical aperture 18 formed in the jaw 13 has rotatably mounted therein a disc-shaped cutting blade 19 and two rubber or knurled cylindrical metal friction rollers 20 and 21 on a shaft 22. The rollers 20, 21 and the intermediate cutting blade 19 are rigidly secured together by two pins 23 to form one composite rotatable unit.

2

A recess 24 formed in the jaw 11 has an insert 25 rigidly mounted therein by means of screws 26 (Figs. 1 and 5). This insert 25 has an undercut milled therein whereby a rectangular shaped slot 27 is provided in the lower jaw 11 to normally receive a small arcuate segment of the cutting blade 19. Two surfaces 29 and 30 formed on the lower jaw 11 are normally in contact with the knurled rollers 20 and 21 when no sheet material is inserted therebetween in position to be severed. As a sheet of material 31 is forced between the friction surfaced rollers 20 and 21 and the surfaces 29 and 30, the rollers are pressed upward against the tension of spring 15 and the movement of the friction rollers over the sheet material 31 causes the rollers and blade 19 to rotate and sever or slit the sheet material. The right ends (Fig. 1) of the two jaws 11 and 13 have inwardly beveled surfaces 32 and 33, respectively, which form a mouth to guide the sheet material 31 to the cutting or slitting position.

In the operation of the cutting device, the device is manually gripped by the handle 12 and is moved into engagement with the edge of a sheet of material to be severed. The sheet of material is guided by the beveled surfaces 32 and 33 to a position between the jaws 11 and 13. As the sheet material is forced under the friction surfaced rollers mounted in the upper jaw, the rollers, being under compression from the leaf spring, will frictionally engage the sheet material thus causing the rollers to be rotated as the cutting device is moved forward. The rollers, being smaller in diameter than the cutting blade, cause the periphery of the cutting blade to travel at a greater rate of speed than the rollers and thus actually to cut or slit the sheet material. Manifestly, the handle 12 could be held in a stationary fixture, and a sheet of material moved through the jaws 11, 13 to cut or sever the material.

It is to be understood that the above-described arrangements are merely illustrative of the application of the principles of the invention and that numerous other arrangements and applications may be devised by those skilled in the art which will embody the principles of the invention and will fall within the scope and spirit thereof.

What is claimed is:

1. A cutting device comprising a spring-pressed hinged member and a fixed member, said hinged member having mounted therein for rotary movement a disc-shaped cutting blade and two cylindrical friction members, one of said cylindrical members being secured to each

side of the cutting blade, said cylindrical members normally being pressed by the spring against sheet receiving surfaces on the fixed member, said fixed member having a recess therein, a slotted insert secured within the recess for receiving a small segment of the cutting blade within the slot, said cylindrical members driving the cutting blade as sheet material is moved between the cylindrical members and the sheet receiving surfaces of said fixed member.

2. A cutting device comprising a fixed lower jaw member having an extended portion, a movable upper jaw member hingedly mounted on said lower jaw member, resilient means carried by the extended portion of said lower jaw member for urging the two jaw members together, said lower jaw member having a blade receiving slot therein, a rotary cutting blade carried by said upper jaw member, and a knurled cylindrical roller secured on each side of said blade, said rollers being forced by said resilient means to normally bear against the surfaces adjacent the sides of the blade-receiving slot on the lower jaw member.

3. A cutting device comprising upper and lower jaw members having inwardly tapered portions to provide a guiding mouth for sheet material, said upper jaw member being hingedly mounted on the lower jaw member, resilient means secured to the lower jaw member for normally urging the upper jaw member toward the lower jaw member, said lower jaw having a blade-receiving slot therein a rotary cutting blade carried by the upper jaw member, and a cylindrical friction roller secured on each side of the blade, said rollers being forced by said resilient means to normally bear against the surfaces adjacent the sides of the blade receiving slot on the lower jaw member, said blade being rotated by manually moving a sheet of material through the guiding mouth into contact with the rollers to transmit movement of the material to the rollers so that the blade is rotated to cut the material.

4. In a hand tool for slitting sheet material, a handle having a first jaw formed integral therewith, a second jaw pivotally secured to the first jaw, a circular cutting member rotatably secured to the second jaw, knurled cylindrical rollers attached to each side of the cutting member, and a leaf spring secured to the handle and engaging the second jaw, said leaf spring acting to force the jaws together so that sheet material positioned between the jaws engages the knurled surfaces of the rollers and movement of the sheet material is imparted to the rollers to rotate the cutting member to sever the sheet.

5. A cutting device for sheet material comprising a lower jaw member having a recess therein and an extended portion, an upper jaw member hingedly mounted on the lower jaw member, each of said jaw members having inwardly tapered portions to provide a guiding mouth for the sheet material, a disc-shaped blade rotatably mounted in the upper jaw member, a slotted insert positioned within said recess in the lower jaw member to receive a small segment of the blade, and a resilient leaf spring secured to the extended portion of the lower jaw member and pressing on the upper jaw member to urge the upper jaw member toward the lower jaw member so that the blade will rotate to cut the sheet material as it passes between the jaw members.
